VISCOSIMETER

George E. Bock, Seattle, Wash., assignor, by direct and mesne assignments, to National Technical Laboratories, Pasadena, Calif., a corporation of California

Application March 13, 1936, Serial No. 68,665

5 Claims. (CL 265—11)

This invention relates to viscosimeters and particularly to a torsion-type viscosity testing device of the character illustrated and described in U. S. Patent No. 1,746,791 issued to William F. Osborne and dated the 11th day of February, 1930.

The objects of the present invention are to provide a device adapted through its advancements over the referred-to structure to accelerate accurate determination of the viscosity of fluids, to provide a device which acts to obtain increased sensitivity in the lower range of viscosity reading, and which otherwise is so constituted and devised as to simplify the structural design and provide an apparatus generally more efficient than heretofore.

The invention consists in the novel construction, adaptation, and combination of parts hereinafter described and claimed.

20 In the drawing:—

Figure 1 is a view, partially in elevation and partially in transverse vertical section, representing the now preferred embodiment of the invention.

25 Fig. 2 is a horizontal section taken on the line 2—2 of Fig. 1.

Fig. 3 is a detail elevation of the rotary cylindrical members in response to the movement of which the liquid is spirally circulated in the spaces which lie between the members and co-active torsionally influenced cylindrical members, the outer of said rotary members being broken away to indicate the manner in which the liquid-circulating threads of the inner rotary member are conversely disposed; and

30 Fig. 4 represents a chart lineated according to the present invention and in conjunction with which the device obtains increased sensitivity for reading low viscosities.

35 The viscosimeter, as illustrated, provides a frame represented by the numeral 6 desirably mounted in a portable casing, the frame being of an inverted-L configuration with the horizontal arm 7 thereof apertured for the passage therethrough of a sleeve 8. I form said sleeve with a shoulder adapted to engage the underside of the arm and provide a threaded end acting to receive a lock-nut 9 which, in its exposed face, is counter-bored for the reception of a bearing 10. Flanged at its lower end and similarly counter-bored for the reception of a bearing 11, the sleeve assembly receives the spindle extension 12 of a disc member 13, the spindle projecting below the bearing 11 and being securably engaged by the hub 14 of a series of concentric radially-

spaced shells 15. I represent said shells as being fixed to the hub through the medium of radial bars 16.

Received in the space between said shells and providing clearance between adjacent peripheries are a pair of concentric cylindrical members 17 which are fixed, as by vertical pins shown dotted in Fig. 1, to vertically-spaced collars 18 revolvably mounted on the sleeve 8. In the space between the bearing collars is a gear 19 for driving the members 17, said gear being in mesh with a motor-driven gear 20. Helical gears are desirably employed although for simplicity in illustration I indicate the gears as of spur form.

Formed in any desired manner, as by pressing or otherwise, said cylindrical members 17 provide spiral threads and these threads, as respects the outer and inner rotating members, are conversely disposed to obtain opposing directional influence upon the liquid which is present between the peripheries of the members 17 and adjacent surfaces of the shells 15.

Reverting to the spindle-actuated disc 13, the same is provided with an integral cam-like pulley 21 in the groove of which a cable 22 is received with the inner terminus thereof lying in a relative diametrically located slot, the pulley having a general involute design emanating at the approximate axis of the disc. The cable lead-off passes about an idler wheel 23 to engage a frame-carried spring 24. Said involute configuration of the pulley surface acts to effect a relative recession, progressively with spring extension, of the contact point of the groove lying in the tangent which defines the cable lead-off, affording a variable lever moment serving to reduce the movement of the disc progressively or relatively so as respects increasing torsion. Conforming to said inverse ratio, a chart as represented by 25 in Fig. 4 indicates, in terms of disc 40 movement, the torsion effective upon the shells 15. Supporting said chart is a concentric drum 26 fixedly connected to the disc, a pointer for the chart being designated by 27 (Fig. 2).

A container for the liquid to be tested comprises 45 a cup 28 adapted to be introduced about the interfitting members 15 and 17 from the underside of the same, the cup being supported by a plate 29 having a pivotal mounting between bracket arms 30 to allow swinging movement of 50 the plate into and from cup-supporting position. Provided by said plate are electrically energized heating elements 31.

Any suitable temperature-indicating device may be employed, the means shown comprising 55

a thermometer 32 of conventional design frictionally held by a rubber ring 33 to submerge the heat-affected bulb 32' in the liquid of the container between the cup and the perimeter of the outer shell 15.

5 The vent holes provided in the fluted members to lie above the level of the liquid within the plate-supported container and which I indicate by 34 allow air to escape as the members 15 and 17 are submerged in the liquid.

10 The operation should be apparent from the foregoing, the container for the liquid being filled to the required level and introduced in the manner shown, following which the plate 29 is swung into supporting position below the container and current caused to flow through the heating elements. Motor-driven revoluble travel of the fluted members 17 circulates the liquid by influencing the same in converse directions longitudinally of 15 the axis of rotation or, otherwise stated, in one longitudinal direction under the influence of the right-hand threads and in the opposite direction under the influence of the left-hand threads, the annular spaces which lie between the members 20 15 constituting relative pumping chambers. As is believed clear, the liquid is circulated automatically in response to rotary movement of the members 17 to effect practically instantaneous distribution of the heat whereby to obtain a uniform 25 temperature throughout the liquid in allowing an immediate reading accurately indicating viscosity by recourse to the indicated thermal condition which prevails.

30 It is intended that the claims be given a breadth in their construction commensurate with the scope of the invention within the art.

35 What I claim is:—

1. In a fluid testing device, the combination of 40 a container for the fluid to be tested, a plurality of revolubly supported annular members disposed in radially-spaced concentric relation and immersed in the fluid within the container, a plurality of revolubly supported annular members interposed in spaced relation to the peripheries of the first-named members in the chambers formed between said first-named members, said interposed members being provided with conversely directed helical threads, means for 45 rotating said threaded members to effect, under the influence of the spiral threads, circulatory movement of the liquid lying between adjacent peripheries of the members, and means for measuring the viscous pull of the liquid upon the cylindrical members adjacent to said threaded members.

50 2. In a fluid testing device, the combination of

revolubly supported annular members disposed in radially-spaced concentric relation, a container for the fluid to be tested and means supporting said container to immerse the annular members in the fluid, means for rotating one of 5 said annular members, and elastic means yieldably resisting the rotary movement of the other of said members resulting from the viscous pull of the fluid lying between the members, said rotated member being formed with helical threads 10 for effecting circulatory movement of the fluid to distribute the heat of the same uniformly throughout the fluid.

3. The structure as defined in claim 2, said immersion of the members in the fluid being 15 afforded by introducing the container from the underside of the members, the support for said container comprising a heating plate pivotally mounted for movement of the plate into and from supporting position.

20 4. In a liquid testing device comprised for revolubly supported annular members disposed in radially-spaced concentric relation and immersed in the liquid to be tested, means comprising a pulley fixedly connected to one of said members, 25 a cable attached to the pulley, and elastic means engaging the opposite end of the cable for yieldably resisting rotary movement of the pulley-connected member, rotary drive means for the other member to actuate the same in revolubly 30 influencing the pulley-connected member oppositely of the elastic resistance according to the viscosity which obtains in the liquid lying between the members, and means including a chart movable relatively in accord with the movement 35 of the pulley-connected member for visibly indicating the viscosity of the liquid, said pulley being formed to an approximate involute configuration to obtain a reduction in the movement of the chart progressively with increasing torsion 40 upon the pulley-connected member.

5. The combination in a testing device comprising a torsionally influenced member, of a pulley influenced by said member, a cable connected at one end with the pulley and at its other end with elastic means yieldably resisting 45 rotary movement of the pulley, and visible indicating means influenced relatively with the movement of the pulley for indicating the torsion-influenced movement of the member, the cable-contacting surface of said pulley being formed to 50 an approximate involute curve to effect variable movement of the indicating means to increase the sensitivity thereof through a selected range of movement of the indicating means.
